UNITED STATES PATENT OFFICE.

PETER SARTORY, OF BAYSWATER, LONDON, ENGLAND.

HAIR CURLER AND WAVER.

Application filed February 1, 1922. Serial No. 533,360.

This invention relates to mechanical hair curling appliances applicable for use in processes of permanently waving natural hair on the head, and likewise for permanently 5 curling or waving artificial or dead hair at the bench.

The object of the invention is to provide a new and improved curling appliance for tensioning and stretching the hair wound 10 thereon and also to provide improved means for clamping the curler to a tress of hair, while a further advantage of the invention is that the curlers for permanently waving the hair may be made of larger diameter 15 than has hitherto been practicable.

In known processes of permanently curling or waving natural hair on the head, or dead or artificial hair at the bench, a tress 20 of hair is tightly wound upon and tied to a mandrel so as to retain the hair under tension for further treatment.

In processes of permanently waving natural hair, mechanical curling appliances are usually employed for tensioning the hair, 25 each appliance comprising a rotatable tube mounted upon a relatively fixed rod, in combination with a ratchet and detent, or other positive or frictional clutch mechanism, adapted to lock the tube when a tress of 30 hair is tightened thereon. The rod projects from one end of the tube and is tied close up to the roots of the tress of hair, the latter being then helically wound upon and tied to the rotatable tube, whereon the wound 35 tress of hair is tightened by suitably turning the tube, while firmly holding the projecting end of the relatively stationary rod.

The tensioning and stretching of the tress 40 of hair wound on such curlers is difficult to control, and is frequently very unequal, a relatively small part being severely strained, while the remainder is left relatively slack, which is detrimental to the success of the waving process.

According to this invention, the rotatable 45 tube or mandrel of a hair curling appliance of the kind referred to, comprises a plurality of tubular sections, each of which can be rotated independently of the remaining 50 section or sections.

Such composite mandrel is carried on an axis member or spindle, to which one of the 55 rotatable tubular sections is connected by suitable positive or frictional clutch mech-

axis or spindle, when the hair coiled thereon is in tension; while the axis or spindle projects from one end of the composite mandrel, so that the appliance can be secured to a tress of hair.

60

The composite mandrel may comprise two rotatable sections, but preferably comprises two opposite end sections separated by intermediate sections.

In either case, the rotatable section at one 65 end of the mandrel is connected by a detent or by a positive or a frictional clutch or like mechanism, with the axis member or spindle, while the length of the composite mandrel can be varied by reducing or increasing 70 the number of its independently rotatable sections.

The several mandrel sections may be each 75 formed with a spigot, or be otherwise adapted to fit together end to end to form a composite mandrel which can be rotated as a whole on its axis or spindle, while when one of such sections is locked, the adjacent or the remaining section or sections can be rotated independently thereon, on the application 80 of a sufficient torque, the socket end of the adjacent section then journaling on the spigot end of the locked section.

Alternatively, the several mandrel sections may be strung together on a suitable 85 axis or spindle, to form a sectional mandrel which can only be rotated as a whole when the tress of hair wound thereon is tensioned. In the latter case the axis or spindle is of sufficient length to extend through all the 90 sections of the mandrel, while in the former case the axis or spindle may be short, so as to extend into the adjoining end section of the mandrel, or be prolonged through all the sections of the latter.

95

When the several rotatable mandrel sections are connected together by spigots, the latter may be grooved or recessed, and be furnished with spring detents that engage the socket ends of the adjacent sections, so 100 that relative rotation of the sections can take place in one direction only.

A composite mandrel so constructed, is 105 preferably carried on a short axis member or spindle that is connected to the adjacent end section by means of a similar detent, so that such section can rotate in one direction only on the axis or spindle, or any suitable positive or frictional clutch mechanism may be provided for locking such 110

mandrel section to the axis or spindle when the tress of hair coiled on the composite mandrel is in tension.

When the axis or spindle is prolonged

- 5 through all the independent rotatable sections, the outer or opposite rotatable end section is connected to the axis or spindle by novel locking means. For this purpose such opposite mandrel section is split and pro-
- 10 vided with a screw clamp, or the like, whereby the split section can be tightened as required on the axis or spindle. By the application of a sufficient torque through a suitable lever, the section can be rotated on
- 15 the spindle in either direction as required to tension the hair wound thereon, the hair being retained under tension by reason of the friction lock between the spindle and the split section.
- 20 Each of the mandrel sections may be stiffened by an internal flange, perforated disc, or the like, that journals on the axis member or spindle when this extends through the several sections of the composite mandrel.
- 25 Such stiffening means also enable the tubular sections to be made in different diameters so that by interchanging one set of sections with another set, composite mandrels of various diameters can be carried
- 30 upon the same axis member or spindle.

The axis member or spindle is preferably tubular, to allow the employment of a novel adjustable clamping device for securing the curling appliance to a tress of hair without

- 35 tying.
- Such clamping device comprises a fixed boss or cross piece mounted on the projecting end of the tubular axis member or spindle, and an adjustable hook, the shank 40 of which is screwed and passes through the tubular axis member or spindle, and is secured and adjusted by means of a screwed sleeve or nut at the opposite end of the tubular spindle, while the returned end of such hook engages a slot or perforation in the 45 boss or cross piece and forms a loop therewith.

Alternatively, a screw flexible member, such as a Bowden wire, may be substituted 50 for a rigid hook, the flexible member passing through the tubular spindle, its outer end being detachably secured to the boss or cross piece to form a flexible loop that is tightened by means of a screw sleeve or nut 55 at the opposite end of the tubular spindle.

The improved appliance is readily secured close up to the roots of a tress of hair by means of the improved clamping device, but if preferred the appliance may be otherwise secured to the tress of hair. The latter is 60 then wound upon the composite mandrel and secured thereto by means of a clip or otherwise as preferred.

A clip for this purpose comprises two 65 arms which lie parallel with the mandrel

and form a sort of cleat for securing the end of the coiled tress of hair, the points of which may then be neatly confined in any convenient manner.

The coiled hair is then evenly tightened 70 and stretched on the composite mandrel by turning the same with a suitable key, or other means, while firmly holding the projecting spindle. As the coiled hair becomes tightened and stretched it successively locks 75 the several rotatable sections of the mandrel until it is evenly stretched and tightened to the extent required.

Any return movement of the several sections of the composite mandrel is prevented 80 by reason of the detents, or other positive or frictional locking means employed, the coiled hair being retained under tension for further treatment.

The several mandrel sections may be perforated to allow of such sections being independently adjusted by means of a key or the like, when the coiled hair is in tension, the hair being displaced to allow of the engagement of a key with a perforation as 90 required.

My invention is illustrated by way of example in the accompanying drawings, in which:

Fig. 1 is a side view of one form of a 95 curling and waving appliance embodying the present invention,

Fig. 2 is a detail view of the tubular spindle,

Figs. 3 and 4 are detail views of one of 100 the rotatable mandrel sections employed therein, all drawn to an enlarged scale,

Fig. 5 is a side view of a modified construction of curling and waving appliance 105 in accordance with the present invention,

Figs. 5^a, 6 and 7 are detail views drawn to an enlarged scale, further illustrating the construction thereof,

Figs. 8 and 9 are respectively side and 110 end views of a further modified construction of curling and waving appliance in accordance with the present invention, and

Figs. 10 and 11 are detail views to an 115 enlarged scale, further illustrating such construction.

In each of the constructions illustrated, the curling and waving appliance is provided with a composite mandrel that comprises a root end section 1 and an opposite end section 2, between which intermediate 120 sections 3 are arranged, the composite mandrel so formed being in each case carried on a tubular axis member or spindle 4.

As shown in Figs. 1 to 4, each of the mandrel sections 1 and 3 is provided with a grooved or recessed spigot 5, on which are secured spring detents 6, (see Figs. 3 and 4). The spigots 5 of the several mandrel sections are adapted to fit into the socket ends 125 of the adjacent section to form a composite

mandrel that can be rotated as a whole, while when one such section is locked, the adjacent socket section can be independently rotated on the spigot 5 in one direction only, 5 by reason of the spring detents 6.

The root end section 1 is coned, and is mounted on a short tubular axis member or spindle 4 that projects from one end of the section 1. As shown in Fig. 2, the spindle 10 4 is provided with a grooved boss 7 that forms a bearing for the coned end section 1, and is provided with spring detents 8 adapted to engage the inner surface of the end section 1, so that the latter can rotate on the 15 spindle 4 in one direction only. The detents 8 are arranged so that the direction of rotation relatively to the spindle 4, is the same as that of the relative rotation of the sections 1, 2 and 3 of the composite mandrel. 20 If preferred, the detents 6 and 8 on the spigot 5 and spindle 4, may be dispensed with, the spigots making a sufficiently tight fit with the adjacent sections, and the boss 7 adapted to make a sufficiently tight fit 25 with the section 1 to prevent rotation except by the application of a sufficient torque. In the latter case the composite mandrel can be rotated as a whole on the spindle 4 in either direction, while the several sections 30 can be independently rotated in either direction when the adjacent spigot section is locked.

In the construction shown in Figs. 5 to 7, the tubular axis member or spindle 4 extends through all the rotatable sections of the mandrel. The mandrel sections 1 and 2 are each formed with a plain spigot end 5^a in which a perforated boss or disc 9 (see Fig. 7), is secured, in order to stiffen such 40 end. When the several sections are assembled to form the mandrel, the latter is supported by the perforated bosses or discs 9 which journal upon the prolonged spindle 4, while the spigot end 5^a of each section 45 makes a frictional fit with the socket end of the adjacent section, so that the composite mandrel can be rotated as a whole upon the spindle 4, while when one of the spigot sections becomes locked, the adjacent section 50 can be independently rotated in either direction on the application of a sufficient torque. As shown in Figs. 5 and 6, the grooved boss 7 on the spindle 4, is arranged to form a bearing for the opposite end section 2 of the 55 mandrel, and is provided with a spring detent 8 adapted to engage internal teeth 2^a, see Fig. 5^a, formed all round the inner surface of the end section 2, so that the latter can be rotated past the detent 8 in one direction only, and not in the opposite direction. 60

In the construction shown in Figs. 8 to 11, the composite mandrel is formed with plain cylindrical end sections 1^a and 2^b, and plain cylindrical intermediate sections 3^a, all of 65 which are strung on to the tubular spindle

4, so that each of such sections can be independently rotated in either direction. In this construction, the opposite end section 2^b is connected to the spindle 4 by means of a novel frictional locking device. For this 70 purpose the end section 2^b is split, and is provided with a strong split clamping ring 10 that is furnished with an adjusting screw 11. By tightening up the clamp 10, the split section 2^b is locked as firmly as required to 75 the spindle 4, so that the section 2^b can be turned in either direction by the application of a sufficient torque.

Each of the improved curling appliances illustrated is furnished with a preferred 80 form of clamping device for readily securing the appliance close up to the roots of a tress of hair. Such curling appliance comprises a fixed boss or collar 12, secured to the outer end of the spindle 4 and provided 85 with a lateral extension 13, and an adjustable member that consists of a hook 14 furnished with a screw shank 15 that passes through the tubular spindle 4, and is adjustably secured therein by means of a screwed 90 sleeve or nut 15^a, while the outer end of the hook 14 takes into a perforation 13^a in the lateral extension 13 of the boss or collar and forms a loop with the same. 95

The clamping device can be opened by slackening the sleeve or nut 15^a, a tress of hair is then readily threaded through the loop so formed and clamped by tightening the screwed sleeve or nut. The tress of hair is then coiled upon the composite mandrel, 100 to the opposite end section 2 of which it is secured by means of a detachable spring clip, such as 16 (Fig. 1) which forms a cleat, or the tress may be secured in any other preferred manner. The coiled hair is 105 then tightened and stretched upon the curler by firmly holding the boss 12 and rotating the composite mandrel on the spindle 4.

In the construction shown in Fig. 1, the coiled hair tightens on the end section 1 110 and locks the same, the next section 3 continues to rotate independently of the section 1, until it in turn becomes locked by the tightening of the hair wound thereon, and so on through the entire series of sections, 115 the hair being thus evenly tightened and stretched throughout its length, while the several sections 2 and 3 and the end section 1 are prevented from returning by means of a spring detent so that the hair is retained 120 under tension for further treatment.

In the construction shown in Fig. 5, the hair similarly locks the several mandrel sections as it tightens and stretches thereon, then by continuing to turn the opposite end 125 section 2, the hair can be further tightened so that it successively causes the sections 3 and finally the section 1 to turn with the end section 2.

In the construction shown in Fig. 8, the 130

coiled hair is first tightened on the split end section 2^b and then as it tightens upon the adjacent section, it causes such section to turn with the section 2^b and so on through the entire series of sections until the hair is effectively stretched and tightened throughout its length.

I claim as new and desire to secure by Letters Patent:

- 10 1. In a hair curler and waver the combination of a composite rotatable mandrel formed by a plurality of independently rotatable sections, with an axis member, and means for locking a terminal section of said mandrel with said axis member, to prevent relative rotation between said axis member and said composite mandrel when a tress of hair coiled upon the latter is in tension.
- 15 2. In a hair curler and waver the combination of composite rotatable mandrel formed by a plurality of independently rotatable sections comprising a longitudinally split end section, with a tubular axis member extending through all said mandrel sections each of which journals on said axis, and means for tightening said split terminal section on said axis member for the purpose set forth.
- 20 3. In a hair curler and waver the combination of a composite rotatable mandrel formed by a plurality of independently rotatable sections that comprise a terminal section furnished with detachable means for securing the end of a tress of hair coiled upon said composite mandrel, with a tubular axis member, adjustable means carried by said axis member for securing the latter to the root end of a tress of growing hair, and means for locking said terminal section with said axis member to prevent relative rotation between the latter and said composite mandrel when the curler and waver is in use.
- 25 4. In a hair curler and waver the combination of a composite rotatable mandrel formed by a plurality of independently rotatable sections that comprise a terminal section furnished with detachable means for securing the tips of a tress of hair coiled on said composite mandrel, with a tubular axis member, a perforated cross piece on one end of said axis member, an axial hook adjustably mounted within said axis and adapted to co-act with said cross piece to form a clamp for securing said axis member to a tress of hair, means for axially adjusting said hook in said axis and means for locking said terminal section to said axis member when the curler and waver is in use.
- 30 5. In a hair curler and waver the combination of a composite rotatable mandrel

formed by a plurality of independently rotatable sections comprising a longitudinally slotted terminal section, a detachable double arm clip adapted to fit said slotted mandrel section and form a cleat for securing the tips of a coiled tress of hair, with a tubular axis member, adjustable means carried by said axis member for securing the latter to a tress of hair, and means for locking said terminal section with said axis member to prevent relative rotation between the latter and said composite mandrel when the curler and waver is in use.

6. In a hair curler and waver the combination of a composite rotatable mandrel formed by a plurality of independently rotatable sections comprising a longitudinally split end section furnished with a detachable means for securing the tips of a coiled tress of hair, with a tubular axis member extending through all said sections which journal loosely on said axis, means for securing said axis to a tress of hair, a clamp ring on said terminal section, adjustable means for contracting said ring, and a projecting boss at one end of said tubular axis member for operating the means for securing the axis to a tress of hair.

7. In a hair curler and waver the combination of a composite rotatable mandrel formed by a plurality of independently rotatable sections comprising a longitudinally split end section furnished with detachable means for securing the tips of a coiled tress of hair, with a tubular axis member extending through all said mandrel sections which journal loosely on said axis, a clamp ring on said end section, adjustable means for contracting said ring, a perforated cross piece secured to one end of said axis member, an axial hook member extending through said axis and adapted to form a clamp with said cross piece, for securing said axis to a tress of hair, and means for axially adjusting and securing said hook member in said axis.

8. A hair curler comprising the combination of a composite mandrel formed by a plurality of independently rotatable tubular sections comprising a split terminal section having an integral clamping ring, with a tubular axis member formed with a cross piece at one end, a hook member axially arranged within said axis member having its hook adapted to take into said perforated cross piece, and a rotatable nut member mounted on one end of said hook member adjacent said clamp ring all as and for the purposes set forth.

In testimony whereof I affix my signature.

PETER SARTORY.
